INVENTOR
Marvin Mead.

BY *A. J. St. Brian*
ATTORNEY

UNITED STATES PATENT OFFICE.

MARVIN MEAD, OF MONTE VISTA, COLORADO.

BALING-PRESS.

SPECIFICATION forming part of Letters Patent No. 541,050, dated June 11, 1895.

Application filed January 28, 1895. Serial No. 536,402. (No model.)

To all whom it may concern:

Be it known that I, MARVIN MEAD, a citizen of the United States of America, residing at Monte Vista, in the county of Rio Grande and State of Colorado, have invented certain new and useful Improvements in Baling-Presses; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in baling presses, and consists of the features, arrangements and combinations hereinafter described and claimed, all of which will be fully understood by reference to the accompanying drawings, in which is illustrated an embodiment thereof.

20 In the drawings, Figure 1 is a top or plan view of my improved baling-press. Fig. 2 is a side elevation of the same. Fig. 3 is a vertical longitudinal section taken through the baling-chamber, showing the plunger-lever and the parts connected therewith in two positions and on a larger scale. Fig. 4 is a top or plan view of the power mechanism, the yoke being 25 removed. Fig. 5 is a plan view of the power-base. Fig. 6 is a section taken through the power-base on the line $x-x$, Fig. 4. Fig. 7 is a cross-section taken through the baling-chamber to the right of the hopper (see Figs. 1 and 35 2) looking toward the left from lines $y-y$, the parts being shown on a larger scale.

Similar reference-characters indicate corresponding parts or elements in the views.

Let the numeral 5 designate two bed timbers to which is attached the anchor-shaped base 6 forming the direct support for the circular plate 7 which is connected with the base by posts 8. An arm 9 is pivoted on a center pin 10 passing through the plate 7 and the 40 anchor-base 6. This center pin passes through the inner extremity of the arm. The outer extremity of this arm is provided with an anti-frictional roller 12.

Above the plate 7, and supported thereby, 45 is the power yoke 13 comprising a casting carrying two depending lugs 13^a. This yoke is journaled on a vertical pin or shaft 14 lo-

cated to one side of the pin upon which the arm 9 is pivoted. The lugs 13^a of the yoke are located on opposite sides of the pin 14 and are equi-distant therefrom. The roller on the arm 9 lies in the path of these lugs during a portion of each revolution of the yoke. Hence, the roller is alternately engaged by the two lugs 13^a whereby the arm 9 is actuated twice 55 during each rotation of the yoke.

To the pin on which the roller 12 is mounted is attached one extremity of the connecting rod 15, the opposite extremity of said rod being attached to a lever 16 fulcrumed on the 60 framework 17 of the baling chamber 18. The baling chamber occupies a position intermediate the power mechanism and the lever.

As shown in the drawings, the lever 16 is angular in shape, and may be termed an elbow-lever. This construction allows the connecting rod 15 attached to the lower arm of the lever to move in a line very nearly straight during the operation of the plunger, and is therefore important. The lever 16 is connected with the plunger 20 by a pitman 19 which is pivotally attached to the lever at its elbow or angle.

Mounted upon the baling chamber and hinged to the framework 17 thereof, is the 65 hopper 21 one end of which projects into the baling chamber and occupies a position just above the path of the plunger. This depending projection 21^a of the hopper is attached to the end of the hopper opposite the hinge 21^c. Above the projection 21^a and normally resting upon the framework 17 is a flange or horizontal projection 21^b. This flange is engaged by a spring 22 which allows the hopper a limited movement on the hinge 21^c as the plunger 70 passes under the projection 21^a. The spring 22, as shown, is bow-shaped, and its extremities are hooked under horizontal projections on the framework 17, the center of the spring being depressed to engage the flange of the 75 hopper.

It is evident that the spring shown may be otherwise attached; also that any other suitable construction of spring may be employed.

Made fast to the bed timbers 5 and located 80 adjacent the power mechanism is a plate 23 having one edge curved as shown at 23^a to engage the roller 12 of the arm 9. The function of this plate is to check gradually the re-

bound or backward movement of the plunger, thus relieving the mechanism from the force of the shock or concussion incident to the unresisted return movement of a rebound 5 plunger. This plate may be made of metal, or it may be constructed of wood having its curved friction face protected by a metallic strap.

Fulcrumed on the plate 23 is a lever 24 one 10 arm of which projects into the path of the lugs on the power yoke. To the opposite extremity of the lever is attached a chain 25 or other suitable instrumentality adapted to pass around a sheave 26 located on one of the 15 bed timbers 5. The opposite extremity of this chain is attached to a rod 27 which passes underneath the baling chamber and is connected at its opposite extremity with another chain or cable 28 which passes around a 20 sheave 29 located on the framework 17. The opposite extremity of this last named chain is connected with a rod 30 attached to the plunger. Through the agency of the lever 24 and the means for connecting it with the 25 plunger, the return movement of the latter may be effected independently of the rebound incident to the expansion of the charge in the baling chamber.

The machine is operated by means of a 30 sweep 32 having one extremity attached to the power yoke and further secured by a tie rod 33. To operate the mechanism, the yoke is turned in the direction indicated by the arrow. (See Fig. 1.) The lugs 13^a on the yoke engage 35 the roller 12 of the arm 9 and carry the arm along until the arcs described by the engaging parts diverge sufficiently to release the arm. During the movement of the arm in the direction of the yoke's rotation, the plunger is 40 driven toward the power mechanism through the instrumentality of the connecting rod 15, the lever 16 and the pitman 19. The movement of the arm 9 is sufficient to give the plunger the desired length of stroke. The material fed into the hopper is thus acted upon by the 45 plunger and forced beneath the depending projection 21^a of the hopper. This projection yields upward when engaged by a charge of material, but as soon as the plunger moves 50 sufficiently in the reverse direction, the projection 21^a moves downward behind the charge and folds the loose material so that it will be caught by the next charge, thus making a neat, compact bale. As soon as the arm 9 is 55 released from the power yoke, the expansion of the charge in contact with the plunger causes the latter to rebound suddenly. As the arm 9 moves backward under the influence of this rebound, its roller engages the 60 friction face 23^a and gradually checks the plunger's rebound as hereinbefore set forth. The movement of the plunger will be reversed after each forward stroke through the instrumentality of the lever 24 and its connections 65 comprising the parts 25, 26, 27, 28, 29 and 30, the arrangement of the parts being such that the lugs of the power yoke engage one arm of

the lever 24 and actuate it sufficiently to accomplish this result, just prior to the engagement of the yoke with the arm 9. Hence, the 70 movement of the plunger may be reversed after each forward stroke, regardless of the rebound imparted by the expansive power of a charge in the baling chamber.

Since the power applied to the connecting 75 rod 15 during the operation of baling is a direct pull, said rod may be made small as compared with a construction where the power is exerted by a push on the connecting rod. A small connecting rod in a machine of this class 80 is an important feature, since it reduces to a minimum the concussion or jar incident to the rebound, and also makes the work of the team easier since it diminishes the obstruction placed across the path or circle of travel. 85

Having thus described my invention, what I claim is—

1. In a baling press, the combination with suitable power mechanism, of an upright elbow-lever having its upper arm fulcrumed on 90 the frame and adapted to oscillate in a vertical plane, the baling chamber and plunger located intermediate the power mechanism and the lever, the pitman attached to the elbow of the lever at one extremity and to the 95 plunger at the opposite extremity, and a connecting rod leading from the power mechanism and attached to the lower arm of the lever, substantially as described.

2. The combination with the baling chamber and the plunger, of the hopper hinged to the framework and having a depending projection extending into the baling chamber and terminating above the path of the plunger, and a spring engaging the folder-end of 105 the hopper, substantially as described.

3. In a baling press, the combination with the baling chamber and plunger, of the hopper hinged at one end to the framework of the machine, the opposite end of the hopper 110 having a depending projection forming a folder, and a flange located above the folder, and a spring engaging the flange, substantially as described.

4. In a baling press, the combination with 115 the plunger and baling chamber, of a rotatable yoke, an oscillating arm pivoted on one side of the yoke's center and having an anti-frictional roller lying in the path of projections on the yoke, a suitable connection between the arm and the plunger, and a stationary plate having a curved friction face adapted to engage the roller on the arm, a lever 24 fulcrumed on the stationary plate, and a suitable connection between one extremity of the lever and the plunger, the other extremity of the lever lying in the path of the 120 rotatable yoke, substantially as described. 125

5. The combination with the baling chamber and plunger, and means for giving the 130 latter the forward movement, of the stationary plate 23, and means for imparting to the plunger the return movement, comprising a lever 24 fulcrumed on the stationary plate, a

suitable connection leading from one extremity of the lever to the plunger, suitable guide pulleys which said connection engages, and suitable means engaging the extremity 5 of the lever for actuating the latter, substantially as described.

6. The combination with the baling chamber and plunger, of the rotatable yoke, means connected with the plunger, and actuated by the yoke, for imparting to the plunger the forward movement, a stationary plate 23, and means for imparting to the plunger the reverse movement after each forward stroke, said means comprising a lever 24 fulcrumed 15 on the plate 23, a connection leading from one extremity of the lever to the plunger, and suitable pulleys which said connection engages, the opposite extremity of the lever lying in the path of the rotatable yoke, substantially as described.

7. In a baling press, the combination with the baling chamber and plunger, of the rotat-

able yoke, the oscillating arm actuated by the yoke, suitable connections between said arm and the plunger whereby the movement of 25 the arm, when actuated by the yoke, gives the plunger the forward movement, a stationary plate 23 having a curved friction face lying in the path of the oscillating arm when making its return movement, and suitable 30 means for imparting to the plunger the reverse movement after each forward stroke comprising a lever 24 fulcrumed on the plate 23, a connection leading from one extremity of the lever to the plunger, and suitable guides 35 which said connection engages, the other extremity of the lever lying in the path of the rotatable yoke, substantially as described.

In testimony whereof I affix my signature in the presence of two witnesses.
